(57) **CLAIM**

The ornamental design for a faucet, as shown and described.

DESCRIPTION

FIG. 1 is a perspective view of a faucet;

FIG. 2 is a front elevational view;

FIG. 3 is a rear elevational view;

FIG. 4 is a top plan view;

FIG. 5 is a bottom plan view; and,

FIG. 6 is an elevational view, as viewed from the right and left side.

The broken lines in all views are for the purpose of illustration and are not part of the claimed design.
